UNITED STATES PATENT OFFICE.

LOU SCHARE, OF SEA CLIFF, NEW YORK, ASSIGNOR TO SCHARE BROS. CO., INC., OF NEW YORK, N. Y., A CORPORATION OF NEW YORK.

DESIGN FOR A CANDY UNIT.

Application filed July 7, 1928. Serial No. 27,403. Term of patent 7 years.

To all whom it may concern:

Be it known that I, Lou SCHARE, a citizen of the United States, residing in Sea Cliff, Long Island, New York, have invented a new, original, and ornamental Design for a Candy Unit, of which the following is a specification, reference being had to the accompanying drawing, forming part thereof, in which--

I claim:

The ornamental design for a candy unit as shown.

LOU SCHARE.
